SPRAYING DEVICE

William Martin Vogel, Bloomfield, N. J.

Application December 13, 1938, Serial No. 245,367

6 Claims. (Cl. 299—88)

This invention relates to spraying devices of the character employed for the distribution of liquid insecticide, and such as is shown in my co-pending application, Serial No. 220,041, filed July 19, 1938, and the object of the present invention is to improve the spraying results; to prevent clogging of the air blast and spray openings, and to impart a rotative or swirling action to the air stream and particles of liquid carried thereby.

In certain types of sprayers of the character mentioned, a retractive movement of the piston tends to draw liquid into the piston chamber. While this is prevented in sprayers of relatively expensive or intricate construction through the use of valves, the present invention contemplates the provision of a simple and less expensive means by which this undesirable characteristic may be prevented. The invention has therefore, as one of its objects, the provision of means by which the flow of liquid into the air chamber on retractive movement of the piston is eliminated.

In the accompanying drawing, wherein an embodiment of the invention is shown, Fig. 1 is a sectional view through a spraying device of the improved construction, the section being taken on the line 1—1 of Fig. 2, looking in the direction of the arrows; Fig. 2 is a front elevation of the same; Fig. 3 is an enlarged sectional view through the spray nozzle; Fig. 4 is a front elevation of the apertured cap at the end of the piston chamber; Fig. 5 is a sectional view on the line 5—5 of Fig. 4, looking in the direction of the arrows; and Fig. 6 is a front elevation of the cap with a modified form of opening provided therein.

In the drawing 1 indicates the piston chamber of the sprayer, the same being of the conventional cylindrical form, and generally composed of a rolled-up section of sheet metal having its longitudinal edges seamed together. Mounted for reciprocation within the cylinder 1 is a piston 2 of conventional form, the same being fastened to one end of a piston rod 3 which extends out of the rear end of the piston chamber or cylinder 1, usually through an opening formed in a plug located in that end. The projecting end of the rod 3 terminates in a handle, not shown but of conventional form, to enable the piston to be reciprocated in the manner well known in sprayer construction.

The forward end of the cylinder 1 is closed by a cap member 6 having its marginal edge seamed at 7a to the end of the cylinder 1, said cap being formed with a forwardly extending cylindrical cup portion 4 having a front end or wall 5 provided with three spaced arcuate depressions 7 located around a central protuberance 8 through which a spray opening 9 is formed.

Fitted within the cap member 6 and held therein by frictional fit or by any other suitable means is a cup-shaped member or inner cap 10 provided with a forwardly extending nose 11 of a diameter less than the internal diameter of the cylindrical cup portion 6 so that an annular chamber 14 is formed within the cup-shaped member 6 between the inner face thereof and the protruding nose portion 11 of member 10. Entering into the annular chamber 14 is a siphon tube 15 which extends upwardly from within the liquid supply tank 29 secured to the cylinder 1 in the conventional manner.

The nose portion 11 of the cup-shaped member 10 has its front wall 18 formed with an air blast opening 13 preferably located in alignment with the spray opening 9, the spray opening being preferably of larger diameter than the air blast opening 13.

It is desirable that the space 20 between the front wall 18 of the nose 11 and the front wall 5 of member 6 be definite and of unvarying size and of less width than the width of the annular chamber 14 whereby the amount of liquid ejected out of the spray opening 9 will be regulated. The fixed spacing of these two walls on the members 6 and 11 is governed by means of fixed stops provided by the inner faces of the arcuate depressions 7. Thus, when the cup-shaped member 10 is pressed or otherwise secured in position within member 6, as shown in Fig. 1, the front of the nose portion 11 coming into contact with the inner faces of the depressions 7 will limit the extent to which the member 10 may be inserted within member 6 and at the same time act to positively space the wall 18 of member 11 a definite distance away from the front wall 5 of member 6.

The arcuate depressions 7 are spaced from one another by pressed out-ribs 21 (Fig. 3) which radiate from the protuberance 8 and form at their inner or concave sides radial channels or passages which connect the protuberance 8 with the annular chamber 14. Liquid is drawn through these channels from chamber 14 to the spray opening, the number and size of these channels serving also to regulate the supply of liquid to the spray opening.

Pressed within the nose portion 11 of the member 10 is a cup 22 having an apertured plate portion 23 and a circumferential wall 24, the latter fitting tightly within the nose portion 11, as indicated in Fig. 1, and frictionally holding the cup in place and locating the wall portion 23 at 35 a distance from the front wall 18 of the nose. The cup 22, which is shown in detail in Figs. 4 and 5, is formed with several apertures 25 which are produced by slitting the wall 23 and distorting portions of the wall adjacent the slits to pro-

vide a tapering passage or hood 26 near each slit.

In operation, movement of the piston in a direction toward the wall 22 will cause the air displaced by the piston to be forced through the passage 26 and out through the openings 25 with a swirling motion, the air so directed passing through the air blast opening 13, drawing liquid through passages 21 and ejecting it in a swirling fine mist out through the spray opening 9. Upon retractive movement of the plunger it has been found that while a small amount of liquid might possibly be drawn through the air blast opening 13 into the space within the nose 11 between the wall 18 and plate 23, the liquid will not be drawn through the apertures 25 and into the piston chamber, and any liquid in said space will be blown out on the following forward movement of the piston.

While the particular formation of apertures 25 and accompanying tapered passages 26 has been found especially effective in imparting a swirling movement of air forced through them and also effective in preventing liquid from being drawn into the piston chamber, other forms of apertures in the plate 22 might be equally as effective. For example, in Fig. 6, the cup 22 is shown as having its plate portion 23 formed with a plurality of small holes 33 which break up the air stream, causing a swirling motion of the same within the nose portion 11 and also preventing liquid to be drawn into the inside of the piston chamber. Various other modifications may also be made without departing from the spirit of the invention.

35. What I claim is:

1. A sprayer having an air cylinder, a piston mounted for reciprocating movement therein, a closure cap disposed over one end of said cylinder, said closure cap having a forwardly extending nose portion, said nose portion having a centrally located spray opening, a cup member fitted within the nose portion, said cup-member having a forwardly projecting central portion having a front wall located adjacent to but spaced from the forward end of the nose portion, an air blast opening formed in said front wall, a cup fitted within the forwardly extending central portion of the cup member, said cup having a closed end spaced from the front wall of the central portion of the cup member, said closed end of the cup being formed with angularly disposed passages leading to openings formed through said closed end.

2. A sprayer having an air cylinder provided with a closure cap at one end, an inner cup-member fitted within the closure cap, the inner cup-member having a projecting portion extending within the closure cap near to the rear face of the front end of said cap, the shapes of said projecting portion and closure cap being such as to form an annular chamber between them, spaced projections formed on the front end of the closure cap and projecting inwardly therefrom and in abutment with the front end of the projecting portion of the cup-member, aligned openings through the closure cap and cup-member, said openings constituting a spray opening and air blast opening respectively, and radial passages formed in the front end of the closure cap between the projections thereon, said passages communicating at one end with the opening in the closure cap and at the other end with the annular chamber located between the closure cap and cup-member.

3. A sprayer having an air cylinder, a piston mounted for reciprocating movement therein, a closure cap disposed on one end of said air cylinder, a cup-member fitted within the closure cap, said cup member having a forwardly extended reduced portion provided with a front end extending close to the front end of the closure cap, the shape of said forwardly extended portion of the cup-member being such as to form an annular chamber between it and the closure cap, a liquid-supply tank supported by the cylinder, a siphon tube extending from within the tank and communicating with the annular chamber, the front end of the cup member being provided with an air-blast opening, the front end 15 of the closure cap having a spray opening, and the front end of the closure cap having radial passages connecting the annular chamber with the spray opening.

4. A sprayer having an air cylinder provided with a cupped closure cap at one of its ends, said cap being provided with a spray opening, an inner cap located within and enclosed by the closure cap, said inner cap having a nose portion extending within the closure cap and so shaped 25 as to form an annular liquid-siphon chamber between itself and the closure cap, a communication between said chamber and a source of liquid supply, said nose portion being provided with an end wall located adjacent to the front 30 end wall of the closure cap, the nose portion of the inner cap being provided with an air blast opening located in proximity to the spray opening, and a cup-shaped member located within 35 the nose portion and provided with a plurality of openings extending through it.

5. A sprayer having an air cylinder, a piston mounted for reciprocating movement therein, a closure cap extending over one end of the cylinder, a cup member nested within the closure cap 40 and shaped to form an annular chamber between it and the closure cap, a communication between said chamber and a source of liquid supply, closure cap having a spray opening, the cup member having an air blast opening, and a 45 separating member of cup form fitted within the cup member and disposed between the piston and the air blast opening, said separating member being provided with a plurality of hooded openings, the hoods extending over said openings being angularly disposed with respect to one another.

6. A sprayer having an air cylinder, a piston mounted for reciprocating movement therein, a closure cap extending over one end of said cylinder, said closure cap having a forwardly extending nose portion provided with a centrally located spray opening, a cup member fitted within the nose portion and having a reduced portion shaped so as to form an annular chamber between itself and said nose portion, a communication between said chamber and a source of liquid supply, said cup member having an air blast opening extending through it in proximity to the spray opening, a cup nested within the cup member and co-operating therewith in the formation of a chamber within the cup member, said cup having a wall interposed between the piston and the air blast opening, said wall having a plurality of openings all of which are 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280
